UNITED STATES PATENT OFFICE

MAX STELLMACHER, OF BERLIN, GERMANY

SWIMMING BELT

Application filed May 28, 1928, Serial No. 281,227, and in Germany June 1, 1927.

The present invention relates to a floating and life-saving device which is constructed as a girdle or belt. An important advantage thereof resides in the fact that owing to it being constructed as a girdle it has a twofold use, on the one hand as a belt and on the other hand as a floating and life-saving device. Moreover the construction may be such that in purely external appearance it is not noticeably distinguishable from an athletic belt.

In this consists the exceptional value of the invention. It enables aquatic sporting men, torists, and anyone who is fond of the water to wear at all times without it being noticed a swimming and life-saving device on the body as a part of the clothing, the device therefore always being at hand in cases of urgent need.

Personal vanity, which hinders many persons who are fond of the water, particularly owners of aquatic sporting vessels, from participating in one of the known and usually noticeable floating and life-saving devices, has already occasioned many misadventures. There is accordingly an urgent need for a means of taking into account this purely human weakness, and this means is provided by the invention hereinafter described in detail in various constructional forms.

The invention is illustrated by way of example in the accompanying drawing, wherein

Fig. 1 shows the device as an athletic belt in its normal condition.

Fig. 2 shows the device in an inflated condition.

Fig. 3 shows the buckle part of the belt in a special constructional form with a special longitudinal fold, and

Fig. 4 shows the other part of the belt in a further constructional form and with another longitudinal fold.

Figs. 1 and 2 illustrate a constructional form in which a tubular body *a* closed at both ends is constructed as a girdle or belt. It will be seen from Fig. 1 that this is effected by one end of the tube overlapping the other end to a considerable extent.

In this instance the one end *g*¹ of the tu-

bular body is connected with a clamping buckle *i*, while the part *g* of the other end comprises a device which, when the belt expands, that is, when it is employed as a floating device, prevents the end from slipping through the clamping buckle *i*.

In the drawing a simple pin *h* is provided by way of example, which is inserted through the end *g* formed as an eye.

To diminish the breadth of the girdle, or to enable it to attain a larger volume of air the tubular body may be folded as desired, for instance as illustrated in the sections *i* and *m* shown in Figures 3 and 4.

Figure 1 shows the device in its normal form, adapted to be worn as a belt. Figure 2 shows the floating and life-saving device produced therefrom by expansion and inflation, the belt being widened right to its stop *k*, thereby enabling it to be slipped under the arms, so that it forms a thoroughly reliable supporting body in the water.

The piece of tubing *h*, which is provided with a closure member such as a plug, enables the device to be inflated. This piece of tubing is arranged on the inside of the end of the tubular body connected with the clamping buckle, so that it is covered up when the device is being worn as a belt. In Figure 1 the piece of tubing is shown hanging down, in order that it may be visible and thereby assist in the comprehension of the device.

A holding member is also provided, which, when the device is being worn as a belt, holds the overlapping end of the tubular body on the other end.

A string fastened in the neighbourhood of the buckle *i*, and passed over the head, prevents the swimming device slipping off the body.

What I claim is:

1. A combined life preserver and belt consisting of an elongated and tubular inflatable body normally foldable in the longitudinal direction and closed at both ends to serve as a belt, a combined inflating and closing member for said inflatable body, a buckle connected to one of the end portions of the tubular body for receiving the other end portion of the body to permit the same to be adjusted.

- to any waist measurement with the end portions overlapping, an abutment on the other end portion of the body for coacting with the buckle to prevent said end portion slipping through the buckle when the body is inflated, and a holding member for retaining the overlapping portions of the tubular body together when the device is used as a belt or preserver.
- 10 2. A flexible tubular bathing belt of impermeable fabric, said belt having its external surface normally held in folds extending longitudinally of the belt and having in-turned pleats extending in opposite directions to form a girdle of narrow width adapted for supporting or confining a garment and expandable by inflation to form a buoyant belt for floating the wearer.
- 15 3. A buoyant bathing belt comprising a longitudinally pleated tubular external section having a valved aperture therein, means preventing the expansion of the end sections of said pleats, straps fixed to the folded ends of said tubular section, and fastening means
- 20 25 for connecting said straps.
4. A buoyant bathing belt comprising an external tubular section creased along a longitudinal fold, means preventing the unfolding of the folded ends of said section and
- 30 fastening means connected with the ends of said tubular section.

In testimony whereof I have signed my name to this specification.
